UNITED STATES PATENT OFFICE.

RUSSELL V. JUDSON, OF DETROIT, MICHIGAN.

GRAIN-SORTING MACHINE.

Application filed July 1, 1920, Serial No. 393,385. Renewed February 5, 1927.

This application is in certain respects a continuation of my Patent No. 1,366,665, issued January 25, 1921, but includes improvements and modification of the structure therein shown. The purpose of this invention is to provide a machine for mechanically and automatically separating grain of a poorer grade from grain of a better grade with which it is mixed and also for cleaning out dirt and foreign substances from the mixture. It comprises the features and elements of construction and their combinations hereinafter described and shown in the drawings as indicated by the claims.

In the drawings:—

Fig. 1 is a vertical sectional view of a machine embodying this invention.

Fig. 2 is a fragmental top plan view of the same with certain parts shown in section.

Fig. 3 is a detail elevation of the bearings for the outer ends of one pair of sorting rolls together with the roll cover and discharge spout associated therewith.

Fig. 4 is a detail section as indicated at line 4—4 on Fig. 3.

Fig. 5 is a transverse section taken through a pair of picking rolls and their cover as indicated at line 5—5 on Fig. 2.

Fig. 6 is a detail section of a drive pinion for the sorting rolls.

Fig. 7 is a section similar to Fig. 4 showing certain features of the roll-cover construction.

Fig. 8 is a vertical sectional view of a modified form of distributor, and illustrating a novel method of feeding and distributing the grain.

Fig. 9 is a vertical sectional view of another modification in the distributor construction.

Fig. 10 is a bottom plan view of the distributor plate shown in Fig. 9.

Fig. 11 is a detail vertical section on a large scale showing the agitating means for the distributor plate.

The machine illustrated in the drawings is of the type comprising a central receiving and distributing hopper, or holder, for the grain around which are arranged radially extending rolls geared together in pairs and mounted for bodily revolution about the central vertical axis of the distributing hopper. The hopper is provided with ports each leading to the trough formed by a pair of co-acting sorting rolls and the grain escaping from the hopper through these ports is carried by

centrifugal force (arising from the revolution of the rolls) along the trough outwardly in radial direction and discharged at the ends of the rolls into a convenient receptacle. The sorting rolls are made with somewhat yielding surfaces preferably of a rubber-like composition which tend to frictionally engage the rougher particles of grain and the irregularly shaped particles of dirt or small stones which may be fed over the rolls and this frictional engagement operates to feed these rougher particles between and through the pair of cooperating rolls so that they can be collected separately from the smoother and more nearly perfect grain which is carried by centrifugal force over the entire length of the sorting rolls and discharged radially at their ends. This general method is not now novel and my invention consists in the various specific improvements in the devices and their mode of use as hereinafter set forth.

Referring to Figure 1 it may be understood that the machine is supported upon suitable legs, 1, extending from a stationary frame, 2, having a central vertical bearing, 3, in which the vertical shaft, 4, is carried. This shaft supports for rotation a frame, or carrier, 5, upon which is centrally mounted the distributing hopper comprising a peripheral wall, 6, and a bottom, 7. The frame also supports a plurality of pairs of sorting rolls, 8, and suitable journals therefor. The carrier, 5, is revolved by means of a horizontal drive shaft, 9, having a bevel pinion, 10, meshing with a bevel gear, 11, secured to the under side of the carrier at its central portion. A step pulley, 12, on the outer end of the shaft, 9, provides for varying the speed of revolution by the usual method of shifting the belt, not shown. If desired, a steady bearing, 13, may be provided for the outer end of the shaft, 9, beyond the pulley, 12.

In the machine illustrated the carrier, 5, is not rigidly secured to the shaft, 4, but is arranged to rotate thereon and said shaft, 4, serves for independently transmitting rotation to a master gear, 14, secured to its upper end. This gear meshes with a plurality of bevel pinions, 15, one of which is carried on the inwardly extending end of the shaft of one of the two sorting rolls which comprise each pair previously mentioned. The remaining roll of each pair is driven from the first through spur pinions, 16, carried by their respective shafts. Thus, the two rolls of each

pair turn in opposite directions and toward each other at the upper side so as to feed between them the rough particles in the manner already described. Heretofore the master gear, 14, has been rigidly mounted with respect to the frame, 2, remaining stationary while the carrier, 5, revolved about it. Thus, the speed imparted to the rolls, 8, was directly proportional to their rate of bodily revolution.

My experience has shown that in operating upon various kinds of grain it is desirable to change the relation between the speed of bodily revolution and the speed of rotation of the sorting rolls so that some classes of material may be subjected to more centrifugal force than others and travel along the troughs between the rolls more rapidly than others without necessarily altering the speed at which the rolls turn and the resulting frictional hold which said rolls can obtain upon the grain. Therefore, in the present machine the master gear, 14, and its shaft, 4, are driven though a bevel gear, 17, and pinion, 18, by a shaft, 19, extending parallel to the shaft, 9, and connected thereto by spur gears, 20, and 21, as seen in Figure 1. By replacing the gears, 20 and 21, with other gears of different ratio it is evident that the speed of the shaft, 19, and the resulting speed of the master gear, 14, may be varied with respect to the speed of shaft, 9, and the resulting speed of the carrier, 5, which it drives. Thus, the ultimate speed of rotation of the pairs of sorting rolls, 8, is of differential nature and with the particular gearing shown in Figure 1 it would be somewhat less than if the master gear, 14, were stationary because with this gearing as shown the master gear, 14, will revolve in the same direction as the carrier, 5, and the resulting difference in their speeds will be less than if the master gear stood still. It will be evident that other gear ratios or gear sets may be substituted for the gears, 20 and 21, to secure any desired relative speed for the master gear, 14, and for the rolls themselves.

The steadyng or outboard bearing 13, is mounted on a two-part standard, the upper part thereof, being removably secured to the lower part by the bolts as shown, the lower part being stationarily secured to the floor by any suitable means that will insure it against displacement; and when it is desired to remove the bearing 13, from the shaft 9, for changing the gears 20 and 21, having first removed the pulley 12, the bolts in the standard will be removed and it will be found that the upstanding lower part of the standard will not interfere with such changes, and that its being stationarily secured to the floor will provide means for replacing the bearing 13, in its proper previous alignment.

As shown in Figure 1, the distributing hopper is provided with a conical bottom, 7, sloping

downwardly and outwardly from its apex which is at the axis of revolution of the carrier, 5. Grain poured upon this cone, 7, as it revolves is thus carried by gravity towards the peripheral wall, 6, and at the same time by virtue of the continuing revolution of the surface, 7, such grain is fairly well distributed over the surface if the rate of delivery thereto is fairly uniform. The wall, 6, is formed with a plurality of ports, 22, (see Figure 2) each leading to the trough formed between a pair of the rolls, 8. In the annular portion, 28, of the casting which includes the wall, 6, the shafts of the roll, 8, are journaled and for lubricating these shafts the casting 80 includes oil-duets, 24, formed in ribs, 25, interposed between the ports, 22, and placed in the angle between the wall, 6, and bottom, 7. Outside the wall, 6, the ducts terminate in bosses, 26, and oil-cups, 27, mounted herein. The ribs, 25, thus serve as partitions to form upwardly open pockets adjacent each of the ports, 22, and in which the grain must collect before passing through said ports. The ribs, 25, are therefore convexly rounded with their wall sloping towards the ports, 22, to assist in directing the grain through the latter.

Each pair of rolls, 8, is provided with a cover, 28, formed as a casting and hinged in position by means of pintle, 29, on a lug, 30, engaging a suitable recess in the wall, 6. Near the outer end of the rolls a second pintle, 31, on lug, 32, is carried in a lug, 33, on the bearing casting, 34, which is provided for the outer ends of the roll shafts. A counter weight, 35, on the cover serves to hold it down and may also be used as a handle for raising the cover for inspection of the rolls at any time. As indicated in Figure 3, the bearing, 34, is cast at its upper side to conform approximately to the shape of the cooperating rolls so that its surface, 36, constitutes an extension of the trough formed by said rolls as further indicated in Figure 4. The cover, 28, is shaped to extend over this portion, 36, of the bearing and terminates just beyond the bearing in a downwardly extending spout, 37, for discharging the grain which successfully travels the full length of the trough.

As shown in Figure 4 the shaft, 38, of each roll is reduced at 39 to form the journal carried in the bearing, 34, and the yielding rubber surface, 40, terminates at the shoulder, 41, thus formed. Washer, 42, of metal, fibre or other wear-resisting material, is carried on the reduced end, 39, against the shoulder, 41, to receive the thrust exerted by the centrifugal force which arises from the revolution of the carrier, 5, and preferably the surface of the bearing, 34, which receives this reaction is provided with depressions or pockets, 43, to hold a limited quantity of lubricant. The centrifugal force being sufficient to hold the washer, 42, firmly in con-

tact with this surface of the bearing casting, 34, effectively prevents any dust or grit from the grain getting into the bearings of the journals, 39.

It is sometimes desirable to remove one or more of the rolls, 8, for renewal of their rubber faces, 40, and in the case of the rolls whose shafts carry pinions, 15, this is expedited by merely reducing the inner ends of these shafts, at 44, and providing no other connection between the shaft and the pinion, 15, than a key, 45, engaging the key slot, 46, in the pinion. The centrifugal force together with the reaction between the pinion, 15, and its driving gear, 14, effectively holds the pinion to the shoulder, 47, of the shaft but upon removal of the outer bearing, 34, the roll shaft, 38, may be withdrawn from its inner bearing in the part, 23, and the pinion, 15, will simply slip off the end of the shaft as it is thus withdrawn.

It sometimes happens that with a given speed of revolution of the carrier, 5, which is desirable for a given variety of grain there will be some particles tending to travel for considerable distances under the influence of centrifugal force and out of contact with the roll surfaces. This might prevent the frictional engagement of some of these particles by the rolls in time, or for a sufficient length of time, to insure their elimination by feeding through the rolls. To overcome this tendency the upper surface of the cover, 28, may be formed with portions trending downwardly as indicated at 48 and thus converging toward the roll surfaces in the direction of travel of grain thereon so that particles striking the rolls near their inner ends and rebounding against the cover will be more promptly deflected down upon the rolls again and particles tending to travel above the roll surfaces will strike these inclined faces, 48, and will likewise be deflected down against the rolls.

As indicated in the drawings and most clearly shown in Figure 5 the two sorting rolls, 8, of each pair are mounted with the axis of one roll in a horizontal plane somewhat above the axis of the other, the lower roll being the forward, or leading roll with respect to the direction of revolution of the carrier, 5, and the upper roll thus serving to sweep the grain around in the path of revolution and prevent it escaping from the trough formed by the two rolls. As a result of this arrangement the impact of the grain as it first strikes the rolls from the port, 22, is borne principally by the lower roll because at this position the centrifugal force is not very great and the grain is fed to the rolls principally by gravity. Therefore, I find it preferable to make the yielding surface, 40, of the lower roll somewhat harder in its consistency than the surface material of the upper roll. This also prevents the grain from

being too strongly engaged by the lower roll upon which it lies when it first arrives in the trough while the softer and more yielding surface of the upper roll which gradually comes more forcibly against the grain as the latter travels outwardly in the trough will take hold of the rougher particles and the dirt notwithstanding their increased velocity as they approach the outer ends of the rolls.

Although Figure 1 shows a conical bottom, 7, for the distributing hopper I have found by experience that this form is not essential. Figure 8 and Figure 9 show distributing hoppers having peripheral walls, 6, which are substantially similar to the peripheral wall of Figure 1 but in which the bottom plates on which the grain is received and from which it is distributed to the ports, 22, are flat instead of conical. In the design shown in Figure 8 the central portion, 50, of the bottom plate, 51, is upraised to give clearance for the upper end of the shaft, 4, while in Figure 9 the length of the shaft, 4, is reduced at 52 rendering such clearance unnecessary so that the bottom plate, 53, presents a perfectly plane surface. With sufficient speed of revolution the grain fed to either of these distributing plates will be carried by centrifugal force outwardly toward the peripheral wall, 6. As shown in 95 the drawings both the plate, 51, and the plate, 53, lie above the circle of ports, 22, so that when the grain reaches the periphery of either form of distributing plate it will be thrown off and will fall into the pocket 100 formed between the successive ribs, 25, and will then be delivered by centrifugal force through the port, 22.

In Figure 8 the casting which includes the hopper wall, 6, is shown with a flange, 54, and the plate, 51, has a peripheral flange, 55, engaging the flange, 54, for centering said plate in the hopper. This leaves an annular space between the edge of the plate and the wall, 6, into which the grain is discharged. The 110 pocket spaces between the ribs, 25, are shown with horizontal bottoms, 56, indicating that gravity is not relied upon to carry the grain through the ports, 22. However, if the centrifugal force is not sufficient of itself the 115 addition of more grain in this pocket fed from above will tend to crowd out the grain already lodged therein and feed it gradually through the port, 22, but since for proper operation of the machine there must be 120 sufficient centrifugal force at any point along the sorting rolls to move the grain outwardly thereon, it is evident that at a point so near the rolls as the port 22 there should be enough force to initiate the travel of the grain.

In the modification shown in Figure 9 the plate, 53, extends substantially to the peripheral wall, 6, but is formed with notches, or ports, 57, each disposed above one of the pockets, 58, which in this instance are shown 130

with outwardly inclining bottom surfaces to assist the grain in rolling toward and through the ports, 22.

I find further by experiment that by merely pouring the grain onto a central distributing plate such as that at 53 if the delivery spout, A, is disposed above the central portion of the plate the grain will be heaped up in a conical pile whose apex angle will acquire a certain limiting acuteness after which additional grain will either roll down over the conical surface of the pile thus formed or its weight will tend to expand the base of the pile so as to force the peripheral grain into pockets 56 or 57, from which it will feed out on to the rolls. Thus, even if the assistance of gravity is desired for feeding the grain from the distributing hopper it can be secured without building a conical bottom into the hopper.

20 When the speed of revolution of the distributor is rather low the feeding of grain therefrom can be materially assisted by vibration of the distributor plate and in the particular machine illustrated this is accomplished quite simply by taking advantage of the usual difference in speed between the master gear, 14, and the carrier, 5. The gear is formed with radial ribs, 59, on its upper surface and the bottom plate, 51, or 53, is provided with cams, 60, arranged in the circle and resembling ratchet teeth as shown in Figures 10 and 11, depending for contact with the ribs, 59, as they pass them. This momentarily jars the distributing plate while guide lugs, 61, on the plate engage guides, 62, on the supporting casting holding the plate in rotative engagement with the carrier.

I claim:—

1. In a grain sorting machine comprising sorting rolls arranged in co-operating pairs, each pair forming a trough for the grain; a bearing member for the discharge ends of the rolls having its upper surface adjoining them and forming a continuation of their trough for discharge of the grain therethrough.

2. In a grain sorting machine comprising sorting rolls arranged in co-operating pairs, each pair forming a trough for the grain and being mounted to revolve bodily about a vertical axis in approximately radial relation thereto, the mountings including a bearing member for the outer ends of the rolls having its upper surface adjoining them and forming a continuation of their trough to permit discharge of the grain thereover.

3. In a grain sorting machine as defined in claim 1, a housing or cover over said bearing member adjacent each pair of rolls to confine and guide the grain in its travel.

4. In a grain sorting machine comprising pairs of rolls, each pair forming a trough for the grain, and means tending to cause the grain to move along the rolls in said trough toward one end thereof for discharge, a

60 housing or covering extending over said

trough, said cover having portions of its surface converging toward the trough in the direction of the movement of the grain therealong.

5. In a grain sorting machine as defined in claim 2, a housing or cover over the trough formed by each pair of rolls and the said bearings therefor, to confine and guide the grain in its travel, said cover continuing therefrom in the form of a downwardly trending discharge spout for the grain.

6. In a grain sorting machine as defined in claim 2, a downwardly trending discharge spout adjacent the bearing member to receive the grain therefrom.

7. In a grain sorting machine as defined in claim 2, a downwardly trending discharge spout adjacent each bearing member to receive the grain therefrom and a collector having an upwardly open receiving mouth over which the spouts travel as the sorting rolls revolve.

8. In a grain sorting machine which comprises a rotating element and sorting rolls mounted substantially radially therein; means for revolving said element about a vertical axis, whereby the rolls are centrifugally thrust endwise against their outer end bearings, said rolls each comprising a core of relatively hard material and a surface of softer and elastically yielding material, and a spacing washer of hard material at the outer end of the rolls, dimensioned for lapping on the end of the hard core and extending radially over the end of the softer outer part, whereby said softer part is protected and the harder core receives the end thrust due to the centrifugal action.

9. In the construction defined in claim 8, foregoing, the outer end bearings of the rolls having lubricant pockets lapped and covered by the washers.

10. In a grain sorting machine which comprises an element mounted for rotation about a vertical axis and sorting rolls carried substantially radially by said rotating element, whereby they are centrifugally thrust endwise against their outer end bearings, said rolls comprising an outer portion of relatively soft material, the outer end journal bearing for said rolls having lubricant pockets in the space around the journal bearing and hard material washers whose outer diameter is substantially the full diameter of said rolls applied on the roll pintles or journals at said outer end, covering the said ends of the soft portion and lapping on said lubricant pockets.

11. In a grain sorting machine comprising sorting rolls arranged in co-operating pairs, each pair forming a trough for the grain and being mounted to revolve bodily about a vertical axis in approximately radial relation thereto, a centrally disposed distributor comprising an upwardly open and substantially

unobstructed feed surface with an upstanding peripheral wall having a series of ports leading to the respective pairs of sorting rolls.

12. In a grain sorting machine as defined in claim 11, said feed surface having the form of a plain cone sloping downwardly from the center toward said ports.

13. In a grain sorting machine as defined in claim 11, said feed surface being substantially flat and terminating at a short distance inwardly from the peripheral wall, and the ports in said wall being disposed below the level of said feed surface.

14. In a grain sorting machine as defined in claim 11, said feed surface being substantially flat and having downwardly opening ports adjacent the peripheral wall, the ports of said wall being disposed below the level of said feed surface.

20 15. In the combination defined in claim 11, said feed surface being mounted to revolve in unison with the sorting rolls.

16. In the combination defined in claim 11, said feed surface being substantially flat but mounted for vertical movement and means for causing vertical reciprocation of said surface to agitate the material thereon and facilitate the feeding action.

17. In a grain sorting machine as defined in claim 11, said feed surface being substantially flat and terminating at a short distance inwardly from the peripheral wall, the ports in said wall being disposed below the level of said feed surface; the annular space between the feed surface and the peripheral wall being divided by partitions into upwardly open pockets with one port of the peripheral wall leading from each pocket.

18. In a grain sorting machine as defined in claim 11, said feed surface being substantially flat and terminating at a short distance inwardly from the peripheral wall, the ports in said wall being disposed below the level of said feed surface; the actual space between the feed surface and the peripheral wall being divided by partitions into upwardly open pockets adjacent the respective ports, said partitions presenting upwardly convex surfaces sloping toward adjacent pockets for feeding material into the pockets by gravity when it lodges on the partitions.

19. In a grain sorting machine comprising sorting rolls arranged in co-operating pairs, each pair forming a trough for the grain, and a carrier for the rolls mounted to revolve them bodily about a vertical axis in approximately radial relation thereto, said rolls being geared together in pairs and one roll of each pair having a shaft projecting toward the vertical axis of revolution and a pinion on said shaft, a master gear centrally mounted to mesh with said pinions, a shaft for driving the carrier, a shaft for driving the master gear, and intermeshing spur gears, one on the driving shaft of the carrier and one on the

driving shaft of the master gear, whereby both shafts are revolved simultaneously and from the same source.

20. In the combination defined in claim 19, said intermeshing spur gears being interchangeable and replaceable, thereby affording means for causing the shafts associated therewith, to vary their relative rotational speeds.

21. In the combination defined in claim 19, said intermeshing spur gears being located outside of the general frame of the machine, one of said driving shafts extending beyond the said intermeshing gears for mounting a primary driving pulley thereon, and an outboard bearing for said extending shaft comprising a two-part standard having the two parts bolted intermediate its height, the lower part being stationarily secured to the floor in unchangeable relation to the said extending shaft, the upper part having affixed to it a bearing for the shafts, whereby the primary driving pulley and the intermeshing gears may be removed without disturbing the alignment of said outboard bearing.

22. In the combination defined in claim 19, each of said pinions having a key or equivalent means for imparting rotation to its shaft but being freely slideable thereon in radial direction inwardly upon disengagement of the master gear from the pinions.

23. In the combination defined in claim 19, each of said pinions having a key or equivalent means for imparting rotation to its shaft, but being clearly slideable thereon in radial direction inwardly upon disengagement of the master gear from the pinion, each shaft having a shoulder limiting outward movement of its pinion at a position for proper meshing of the pinion with the master gear.

24. In a grain sorting machine comprising sorting rolls arranged in co-operating pairs, each pair forming a trough for the grain and being mounted to revolve about a vertical axis in approximately radial relation thereto, a centrally disposed distributor comprising a substantially unobstructed circular feed surface also mounted to revolve about said axis and within an upstanding peripheral wall having feed ports, leading respectively to the pairs of sorting rolls.

25. In a grain sorting machine as defined in claim 1, a housing or cover extending over the trough formed by each pair of rolls, said cover having formed on the lower surface thereof, a series of abruptly ending inclined planes, said planes converging toward the direction of travel of the grain along the rolls.

26. In a grain sorting machine as defined in claim 1, a housing or cover extending over the trough formed by each pair of rolls, said cover having formed on the lower surface thereof, a series of abruptly ending inclined

planes, the inclination of the said planes being downward toward the direction of travel of the grain along the rolls.

27. In a grain sorting machine comprising 5 sorting rolls arranged in co-operating pairs forming troughs for the grain and a carrier for the rolls mounted to revolve them bodily about a vertical axis in approximately radial relation thereto, a master gear centrally 10 mounted with respect to the carrier and co-operating gears on the rolls through which said master gear operates to drive them about their own axes, a power member for driving the carrier and operative connections there- 15 from to the master gear, said operating connections including speed-changing gearing for altering the speed ratio between the rolls and the carrier.

28. In a grain sorting machine comprising 20 sorting rolls arranged in co-operating pairs forming troughs for the grain and a carrier for the rolls mounted to revolve them bodily about a vertical axis in approximately radial relation thereto, a master gear centrally

25 mounted with respect to the carrier and co-operating gears on the rolls through which said master gear operates to drive them about their own axes, a drive shaft for the carrier and a separate drive shaft for the master gear, together with speed varying connec- 30 tions between said shafts for altering the speed ratio between the rolls and the carrier.

29. In the combination defined in claim 19, 35 said intermeshing spur gears being located outside of the general frame of the machine, whereby they are accessible for changing the speed ratio between the rolls and the carrier without disturbing any interior mechanism of the machine.

30. In the combination defined in claim 27, 40 said speed changing gearing being accessible for adjustment outside of the general frame of the machine without disturbing the interior mechanism thereof.

In testimony whereof, I have hereunto set 45 my hand this 13th day of November, A. D. 1919.

RUSSELL V. JUDSON.
